(57) **CLAIM**

I claim the ornamental design for the preformed artificial nail having flared free edge, as shown and described.

DESCRIPTION

FIG. 1 is a top perspective view of a first preformed artificial nail tip constructed in accordance with teachings of the invention.

FIG. 2 is a plan view of a preformed artificial nail tip of FIG. 1.

FIG. 3 is a side elevational view of a preformed artificial nail tip of FIGS. 1–2, the opposite side elevational view being a mirror image.

FIG. 4 is an elevational view of the proximal end of the preformed artificial nail tip of FIGS. 1–3.

FIG. 5 is an elevational view of the distal end of the preformed artificial nail tip of FIGS. 1–4.

FIG. 6 is a bottom view of the preformed artificial nail of FIGS. 1–5.

FIG. 7 is a top perspective view of a second embodiment of a preformed artificial nail tip constructed in accordance with teachings of the invention.

FIG. 8 is a plan view of a preformed artificial nail tip of FIG. 7.

FIG. 9 is a side elevational view of a preformed artificial nail tip of FIGS. 7–8, the opposite side elevational view being a mirror image.

FIG. 10 is an elevational view of the proximal end of the preformed artificial nail tip of FIGS. 7–9.

FIG. 11 is an elevational view of the distal end of the preformed artificial nail tip of FIGS. 7–10.

FIG. 12 is a bottom view of the preformed artificial nail tip of FIGS. 7–11.

FIG. 13 is a top perspective view of a third embodiment of a preformed artificial nail tip constructed in accordance with teachings of the invention.

FIG. 14 is a plan view of a preformed artificial nail tip of FIG. 13.

FIG. 15 is a side elevational view of a preformed artificial nail tip of FIGS. 13–14, the opposite side elevational view being a mirror image.

FIG. 16 is an elevational view of the proximal end of the preformed artificial nail tip of FIGS. 13–15.

FIG. 17 is an elevational view of the distal end of the preformed artificial nail tip of FIGS. 13–16.

FIG. 18 is a bottom view of the preformed artificial nail tip of FIGS. 13–17.
